DYE ATTACHMENT FOR SEWING MACHINES

Arthur J. Hall, Bakersfield, Calif.

Application September 4, 1951, Serial No. 244,945

1 Claim. (Cl. 101—26)

1

This invention relates to attachments for sewing machines.

A dye or other coloring substance may be applied to a fabric or other desired perforatable material, through the operation of a needle passing through the material in a manner similar to the ordinary operation of sewing, the needle dipping into a well or container of the substance after passing through the material, collecting the substance in the eye of the needle, and then applying the coloring to the material on its return stroke through the material by a wiping action.

A further important object of the invention applies to the provision of the eye of a needle as a carrier of a dye or other liquid coloring substance for application to fabrics, leather, parchment, suitable papers, and other materials to dye or color the same in any desired pattern or arrangement, the needle working in conjunction with a suitably positioned well or series of wells containing the desired coloring substances.

By the use of this invention all sorts of color schemes may be quickly and readily applied to a desired perforatable surface with no more effort and with as much ease as would take place in the ordinary operation of a sewing machine. By this means lamp shades, cover fabrics, and a great variety of objects can be rapidly and cheaply decorated.

With the above and other objects in view, my invention consists in the arrangement, combination and details of construction disclosed in the drawing and specification, and then more particularly pointed out in the appended claim.

In the drawing,

Figure 1 is a vertical section of a dye attachment for a sewing machine, constructed according to an embodiment of this invention.

Figure 2 is a sectional view taken on the line 2—2 of Figure 1.

Referring to the drawing, the numeral 10 designates generally the table of a sewing machine, and the numeral 11 designates a vertical reciprocating needle which is adapted to engage through a guide 12 having an opening 13. The guide 12 is disposed through the table 10, and the upper end of the guide 12 is flush with the upper surface of the table 10.

A disc-shaped receptacle carrier 14 is disposed beneath the table 10 and is formed with a plurality of circumferentially spaced apart openings 15 within which dye receptacles 16 are adapted to dependingly engage. The dye receptacles 16 are formed with an upper annular flange 17 seat-

ing on the upper side of the carrier 14. The carrier 14 is adjustably or rotatably supported from the table 10 by means of a bolt 18, and preferably a washer 19 is interposed between the upper side of the carrier 14 and the lower side of the table 10.

A spring 20 engages about the bolt 18 below the carrier 14, bearing at its upper end against the lower side of the carrier 14, and bearing at its lower end against a spring tensioning nut 21 which is threaded onto the bolt 18. The tension of the spring 20 will yieldably hold the carrier 14 in adjusted position with one of the receptacles 16 disposed below the needle opening 13 in the guide 12.

The table 10 is formed with an opening 22 oppositely from the guide 12, and a cover plate 23 removably engages in the opening 22. The opening 22 provides a means whereby the several receptacles 16 may be refilled with a dye liquid.

In the use and operation of this device, the carrier 14 is suspended beneath the table 10 by the bolt 18, in a position where a selected one of the dye holding receptacles 16 may be disposed in substantial registry with the needle opening 13. A fabric or other flexible article 24 is placed on the upper side of the table 10, whereupon the sewing machine may be operated in the conventional manner without a thread extending through the needle 11. The needle 11 on its downward stroke will pierce the fabric or work 24 and will dip into the dye in the receptacle 16 which is at this time in operative position beneath the needle. The liquid dye will not only coat the needle but will also engage in the eye of the needle so that as the needle is pulled upwardly the dye will be wiped from the needle by the fabric 24.

The work 24 is moved on the surface of the table 10 either by the normal fabric feeding means or by a manual movement of the fabric so that the needle will progress about a predetermined outline of a design which is marked on the upper side of the fabric or work piece 24. By providing a series of dye receptacles 16, each receptacle may have a separate color so that a substantial number of colors may be impregnated in the fabric to form the desired coloring of the design. The thickness of the needle and the weave of the fabric will determine or regulate the width of the marking which is formed by the dye.

I do not mean to confine myself to the exact details of construction herein disclosed, but claim

all variations falling within the purview of the appended claim.

What I claim is:

In combination a marking machine, including a table, a reciprocable needle mounted for movement through said table dye attachment mounted beneath said table comprising a disc-shaped plate formed with a series of circumferentially spaced apart openings, a flanged dye receptacle depending through each opening, a washer on 10 the upper side of said plate adapted to space the latter from the lower side of said table, a pivot bolt extending through said plate and washer and engageable through said table and rotatably supporting said plate beneath said table, and a

spring about said bolt yieldably holding said plate in adjusted position.
